UNITED STATES PATENT OFFICE

LEONARD J. FOX, OF CINCINNATI, OHIO, ASSIGNOR TO FOX COMPANY, OF CINCINNATI, OHIO, A PARTNERSHIP COMPOSED OF LEONARD J. FOX AND MILFORD G. FOX

DEVICE FOR SECURING NAME PLATES AND THE LIKE

Application filed September 11, 1931. Serial No. 562,321.

My invention relates to devices for attaching name plates, such as the plates bearing the names of automobiles and the like, to the openings in walls such as the walls of the 5 radiators in which the name plates are received.

While specifically I will describe my invention as relating to an attaching device for attaching a name plate to an opening in a 10 radiator shell, it should be understood that the same attaching means may be employed for mounting various types of plates to wall openings.

In the art there has been considerable development in the use of attaching devices for name plates which permit of insertion within the opening arranged to receive the attaching devices. These attaching devices, in order to be commercially practical, have in 15 the past been provided with springs and other types of expanding members which automatically expand annular members, and either cause them to frictionally engage the walls of the opening or which cause portions 20 of the attaching devices to interlock against the back wall of the opening.

It is the object of my invention to provide an attaching device formed from a single ring-like member which will expand and 25 interlock against the inner annular corner of the opening arranged to receive the device.

It is a further object of my invention to provide an attaching device which may be made of any stiff metal, having side walls of 30 less diameter than the opening in which it is to be placed, with the inner annular edge of the device of a greater size than the opening, so that the inner annular edge of the device 35 will frictionally engage on the inner corner of the opening without frictionally bearing against the side walls of the opening.

It is a further object of my invention to make a single piece attaching device having 40 inwardly tapered portions which will be

found convenient in assisting in locating the device within the hole which receives it.

It is a further object of my invention to provide an attaching device in the form of what I will call an expansion cup, which may 50 be of any suitable size or shape and of a depth so that the inner annular edges of the cup will extend clear through the hole.

Broadly it is the object of my invention to provide an attaching device made from an 55 integral annular piece which is so slotted and shaped that it may be inserted within an opening with a pushing movement, and which, after being inserted, will resist any normal effort to displace it.

The above objects and other objects to 60 which reference will be made in the ensuing disclosure, I accomplish by that certain combination and arrangement of parts of which I have illustrated a preferred embodiment.

Referring to the drawings:

Figure 1 is a sectional view showing a portion of a radiator shell with the name plate and the attaching device ready for insertion within the opening.

Figure 2 is a sectional view showing the device after it has been secured within the opening.

Figure 3 is a front elevation of the name plate secured in position on the radiator shell.

I have indicated a radiator shell 1 having an inturned flange 2, the inner edge of which is indicated at 3. The opening is of suitable size to receive the cup-shaped expansion member of my attaching device.

A name plate is indicated at 4. To this name plate I have soldered an annular cup-shaped member 5 having slots 6 and with a convex bead or annular rim 7. The slots 6 provide segmental spring members 8 which, 85 due to the formation of the bead 7, tend to resume their normal expanded position, resisting a tendency to be collapsed into cylindrical shape.

The inner end of the cup-shaped expansion 90

member is tapered inwardly, as indicated at 9, so that it may be readily positioned within the opening in the member on which the plate is mounted.

5 To insert the device, the plate is held in the position indicated in Figure 1, and pressed within the opening in the shell. The bead 7, after passing the inner edge 3 of the opening, interlocks in back of the edge, and the 10 slots cause the sections 8 to expand, thus retaining the plate within the opening.

It should be noted that my attaching device does not depend on any frictional engagement of the walls of the opening, because 15 from the position indicated at 10 in Figure 2 until the annular bead or rim 7 is reached, there is no surface contact between the outer wall of the expansion cup and the inner surface of the wall of the shell. This is an important feature of my invention, because it 20 has been found that devices which depend on a frictional interlock for seating are much more susceptible to dislodgment than if there is a positive interlock against the edge of the 25 casing or shell on which the name plate is mounted.

As stated, the attaching device disclosed herein is suitable for mounting any article within the walls of an opening, the particular reference to the name plate of an automobile and the radiator shell being merely for purposes of explanation.

Having thus described my invention, what I claim as new and desire to secure by Letters Patent, is:—

1. A device for attaching a plate to a member having an opening therethrough, comprising a neck extending from the surface of the plate that is to be adjacent to said member, with resilient laterally extended terminal portions adapted to recede for passage of said neck through said opening, and spaced such a distance from said surface of the plate relative to the length of said opening through said member that said terminal portions will extend through the hole and expand into retentive engagement with the edges of the end of said hole where said portions extend through and bind said surface 50 of the plate closely to the adjacent surface of said member, the intermediate extent of said neck between the plate and the terminal portions being substantially less in cross dimension than said opening, whereby the plate is 55 held substantially stationary with respect to said member independently of any engagement of said intermediate extent of said neck with sides of said hole.

2. In combination with a plate to be attached to a member having an opening, a neck on said plate having resilient laterally extended terminal portions spaced from the plate a distance relative to the length of the hole such that said portions will extend 65 through the hole and expand against the ad-

jacent edges of the hole with sufficient tightness to hold the plate firmly to the member, both as regards movement of the plate along or away from the member, the intermediate extent of the neck between the plate and said terminal portions being substantially less in cross dimension than said opening. 70

3. An attaching device for a name plate comprising an integral, tubular member of suitable size and shape to be received within an opening in a supporting member, said tubular member having slots extending in longitudinally from its inner end forming a series of concentric, arcuate-shaped spring leaves, said leaves having outwardly extending portions adjacent their ends providing ridges which spring into interlocking engagement against the inner edge of the opening in the supporting member, the shape of said tubular member being slightly frustoconical, whereby the walls of the device, excepting at the ridged portions, have clearance from the walls in which the opening is formed. 80

4. An attaching device for an article to be mounted comprising an integrally formed cup-shaped member having slots arranged longitudinally in the open end of the cup separating the device into radially spaced spring leaves, each of which has an outwardly extending bead adjacent its end edge, the depth of said cup-shaped member being sufficiently greater than the depth of the walls of the hole adapted to receive the device that the outwardly extending beads will engage and interlock against the inner edge of the wall surrounding the hole, and said cup-shaped member being of less diameter than the diameter of the walls of the hole. 100

5. An attaching device for an article to be mounted comprising an integrally formed cup-shaped member having slots arranged longitudinally in the open end of the cup separating the device into radially spaced spring leaves, each of which has an outwardly extending bead adjacent its end edge, the depth of said cup-shaped member being sufficiently greater than the depth of the walls of the hole adapted to receive the device that the outwardly extending beads will engage and interlock against the inner edge of the wall surrounding the hole, the extreme end edges of the leaves being bent inwardly to assist in entering the device within its mounting hole, and said cup-shaped member being of less diameter than the diameter of the walls of the hole. 110

6. An attaching device for mounting in an opening in a wall shaped to receive it, comprising an open ended tube having an annular rim adjacent its end bent outwardly and inwardly, said end being indented with slots forming radially spaced spring leaves, and said tube being of a smaller diameter than the diameter of the opening. 120

7. An attaching device for a name plate, comprising an integral tubular member having arcuate spring leaves with an outwardly extending bead adjacent the ends of the leaves, said bead being arranged at a suitable distance from the other end of the device so as to interlock with the inner edge of an opening in the wall of suitable shape to receive the device, said tubular member being of smaller diameter than the diameter of said opening.
